CLAIM

The ornamental design for a support pad, as shown and described.

DESCRIPTION

FIG. 1 is a top perspective view of a support pad, showing our new design;

FIG. 2 is a front elevation view thereof, the left side, right side, and rear elevation views being identical images thereof;

FIG. 3 is a top plan view thereof; and,

FIG. 4 is a bottom plan view thereof.

The broken lines shown in the drawings depict portions of the support pad that form no part of the claimed design.
